UNITED STATES PATENT OFFICE.

LOUIS JOBEY AND ULYSSE N. JOBEY, OF BROOKLYN, NEW YORK.

DESIGN FOR A TOBACCO-PIPE.

46,998.

Specification for Design.

Patented Feb. 23, 1915.

Application filed November 9, 1914. Serial No. 871,218. Term of patent 3½ years.

To all whom it may concern:

Be it known that we, LOUIS JOBEY and ULYSSE N. JOBEY, both citizens of the United States, residing at the borough Brooklyn, in the county of Kings, city and State of New York, have invented a new, original, and ornamental Design for Tobacco-Pipes, of which the following is a specification, reference being had to the accompanying drawing, forming part thereof.

The figure shown in the drawing is a side elevation of a tobacco pipe showing our new design.

Copies of this patent may be obtained for five cents each, by addressing the "Commissioner of Patents, Washington, D. C."

We claim as our invention:

An ornamental design for a tobacco pipe, as shown.

Signed by us this 5th day of November, 1914.

LOUIS JOBEY.
ULYSSE N. JOBEY.
